Charles D. Fowles

UNITED STATES PATENT OFFICE.

LLOYD B. SALT, OF DEDHAM, MASSACHUSETTS.

NON-GLARE HEADLIGHT.

1,354,422.

Specification of Letters Patent. Patented Sept. 28, 1920.

Application filed January 16, 1919. Serial No. 271,502.

To all whom it may concern:

Be it known that I, LLOYD B. SALT, a citizen of the United States, residing at Dedham, in the county of Norfolk and State of Massachusetts, have invented new and useful Improvements in Non-Glare Headlights, of which the following is a specification.

This invention relates to head lights, the same being particularly adapted for use on 10 automobiles.

The object of the invention is to provide a head light from which the rays of light are reflected parallel to the axis of the reflector, 15 said rays of light being confined within certain limits and thereby prevented from becoming objectionable by dazzling the eyesight of anyone approaching from a direction opposite to that from which the rays 20 of light are being reflected.

It is still further the object of the invention to obscure the direct glow from the source of illumination.

The invention consists in the combination 25 and arrangement of parts set forth in the following specification and particularly pointed out in the claims thereof.

Referring to the drawings:

Figure 1 is a central vertical sectional elevation of a head light embodying my invention.

Fig. 2 is a horizontal sectional plan taken on the line 2—2 of Fig. 1.

Fig. 3 is a view similar to Fig. 1, illustrating a modified embodiment of my invention.

Fig. 4 is a sectional plan taken on the line 4—4 of Fig. 3.

Like numerals refer to like parts throughout the several views of the drawings.

In the drawings, referring to Figs. 1 and 2, 5 represents a casing of any desired shape or construction, the same having mounted therein a reflector 6, provided with a reflecting surface 7. The reflector is constructed in the form of a parabola and is held in place in the casing 5 behind the usual glass 8 by a rim 9 of any suitable ornamental design or construction.

50 A source of illumination, preferably an electric light bulb 10, is mounted in a socket 11 at the rear of the reflector 6, the filament 12 of said electric light bulb being located at the focal point of said reflector.

55 All the rays of light from the source of illumination striking the reflecting surface will

be reflected parallel to the axis of the reflector.

In order to confine the rays of light within certain limits, a horizontal wall 13 is provided, said wall extending from the glass 8 rearwardly and intersecting the reflector 6. The under face of the wall 13 has a reflecting surface 14 and all rays of light striking said surface will be reflected downwardly. 60 Another horizontal wall 15, which is parallel to the wall 13, extends from the glass 8 rearwardly and intersects the reflector 6. The upper face of this wall has a non-reflecting surface 16, therefore all rays of 70 light striking said surface are prevented from reflecting upwardly and outwardly and becoming objectionable to any one who might be in the direct path of said rays.

A shield 17 is adjustably mounted upon 75 the wall 13 and projects downwardly in front of the source of illumination, said shield being fastened in place by means of a thumb screw 18. The rear face of the shield 17 has a reflecting surface 19 adapted 80 to reflect all rays of light striking the same in a rearward direction. The shield 17 is provided in order that the direct glow from the electric light bulb may be obscured. The front face of the shield 17 has a non- 85 reflecting surface 20.

In operation the head light throws a powerful forward beam of light, all the rays from the source of illumination which strike the parabolic reflecting surface being reflected parallel to the axis of the reflector. 90 The rays of light which pass from the source of illumination upward and especially those which pass upward and forward and would be dazzling to the eyes of a person facing said rays, strike the wall 13 and are reflected downward. The direct rays passing forward from the source of illumination are reflected rearwardly by the shield and those passing downwardly against the wall 15 are 100 absorbed by the non-reflecting surface 16, the result being that all the rays of light which might dazzle the eyes and confuse anyone approaching said head light would be eliminated.

105 It is obvious that the walls 13 and 15 may be vertically disposed if necessary, and the surface of said walls which are exposed to the source of illumination may be adapted to reflect or absorb the rays of light as desired without departing from the spirit of my invention.

In Figs. 3 and 4 is illustrated a modified construction embodying my invention in which a reflector 22 is provided having a reflecting surface 23. In this form, however, the reflector is constructed in the form of a parabola only in the horizontal plane. In the vertical plane the sides of the reflector are perfectly straight or at right angles to the horizontal plane. An elongated electric light bulb is mounted in a socket 25 fast in a slide 26 and has a filament 27 which is located at the focal axis of the reflector 22.

A horizontal wall 28 extends from the glass 8 rearwardly and intersects the reflector 22, said wall having a reflecting surface 29 exposed to the source of illumination. Another horizontal wall 30 extends from the glass 8 rearwardly and intersects the reflector 22, said wall having a non-reflecting surface 31 which is exposed to the source of illumination.

A shield 32 is fast to the slide 26, said shield having a reflecting surface 33 adapted to reflect rays of light from the source of illumination rearwardly and also a non-reflecting front face 35 adapted to absorb any rays of light which might be reflected upon it. The shield 32 together with the electric light bulb 24 are adjustable together with the slide 26 upon the wall 30 and are fastened thereto by a thumb screw 34.

The walls 28 and 30 of this form of reflector together with the shield 32 perform the same functions as do the corresponding walls and shield in the form illustrated in Figs. 1 and 2.

Having thus specifically described my invention, what I claim and desire by Letters Patent to secure is:

1. In a headlight, a reflector, said reflector in its horizontal plane being constructed upon a parabolic curve, and in its vertical plane having straight sides, a pair of parallel horizontal walls intersecting said parabolic curve adapted to confine the rays of

light reflected therefrom, a slide adjustably mounted upon one of said horizontal walls, and a source of illumination mounted upon said slide and located upon the focal axis of said parabolic curve. 50

2. In a headlight, a reflector, said reflector in its horizontal plane being constructed upon a parabolic curve, and in its vertical plane having straight sides, a pair of parallel horizontal walls intersecting said parabolic curve adapted to confine the rays of light reflected therefrom, a slide adjustably mounted upon one of said horizontal walls, a source of illumination mounted upon said slide and located upon the focal axis of said parabolic curve, and a shield adjustably mounted upon said slide, said shield being parallel to the source of illumination and adapted to prevent the emission of direct rays of light therefrom. 60

3. In a headlight, a reflector, said reflector in its horizontal plane being constructed upon a parabolic curve, and in its vertical plane having straight sides, a horizontal wall intersecting the upper portion of said parabolic curve, said horizontal wall having a reflecting surface, a second horizontal wall intersecting the lower portion of said parabolic curve, said second wall having a non-reflecting surface, a slide mounted upon said second named wall, a source of illumination mounted upon said slide and located upon the focal axis of said parabolic curve, and a shield mounted upon said slide, said shield being parallel to the source of illumination and adapted to prevent the emission of direct rays of light therefrom, said shield and said slide being adjustable either independently or simultaneously relatively to each other and to said parabolic curve. 85

In testimony whereof I have hereunto set my hand in presence of two subscribing witnesses.

LLOYD B. SALT.
